Primary Examiner — Mehri F Bajoul(74) *Attorney, Agent, or Firm* — McKee, Voorhees & Sease, PLC(57) **CLAIM**

We claim the ornamental design for packaging for food and condiments, substantially as shown and described.

DESCRIPTION

FIG. 1 is an isometric view of the packaging for food and condiments in an unfolded configuration;

FIG. 2 is a front elevation view thereof;

FIG. 3 is a front elevation view thereof, showing an alternate position for the lid;

FIG. 4 is a front elevation view thereof, showing an alternate position for the lid;

FIG. 5 is an isometric view thereof;

FIG. 6 is a top plan view thereof;

FIG. 7 is a top plan view thereof;

FIG. 8 is a side elevation view thereof; and,

FIG. 9 is a side elevation view thereof.
